Primary Examiner — Anhdao Doan(74) *Attorney, Agent, or Firm* — Nixon Peabody LLP**(57) CLAIM**

The ornamental design for an extraction device, as shown and described.

DESCRIPTION

FIG. 1 is a top isometric view of an extraction device.
 FIG. 2 is a bottom isometric view thereof.

FIG. 3 is a front side elevation view thereof, being identical to a rear side elevation view based on the radial symmetry of the device.

FIG. 4 is a left side elevation view thereof, being identical to a right side elevation view based on the radial symmetry of the device.

FIG. 5 is a top plan view thereof; and,
 FIG. 6 is a bottom plan view thereof.
